UNITED STATES PATENT OFFICE.

GEORGES PROUVOT, OF ROUBAIX, FRANCE.

WOOL BURRING AND PICKING MACHINE.

SPECIFICATION forming part of Letters Patent No. 754,236, dated March 8, 1904.

Application filed January 21, 1903. Serial No. 139,935. (No model.)

To all whom it may concern:

Be it known that I, GEORGES PROUVOT, a citizen of the Republic of France, and a resident of Roubaix, Department of Nord, France, have 5 invented a new and Improved Wool Burrung and Picking Machine, of which the following is a full, clear, and exact description.

My invention relates to improvements in wool picking and burring machines by which 10 I seek to mechanically clean locks of wool from vegetable burs, dirt, and other refuse which may be entangled therewith.

In the treatment of wool by machinery to remove burs and refuse therefrom previous to 15 carding special mechanical devices must be employed to remove the burs without tearing the fibers, and in my invention I have produced an efficient mechanism which combs the locks of wool in order to loosen the fibers 20 or filaments and to bring them into parallel relation, thus opening the locks and spreading out and loosening the fibers, so that they are thoroughly cleaned without unnecessary straining or tearing.

25 Further objects and advantages of the invention will appear in the course of the subjoined description, and the novelty will be defined by the annexed claims.

Reference is to be had to the accompanying 30 drawings, forming a part of this specification, in which similar characters of reference indicate corresponding parts in all the figures.

Figure 1 is a side elevation of a portion of 35 a wool burring and picking machine constructed in accordance with my invention. Fig. 2 is a vertical cross-section on the line 2 2 of Fig. 1. Fig. 3 is a plan view partly broken away. Fig. 4 is a vertical section through the group of feed-rolls. Figs. 5, 6, and 7 are 40 detail fragmentary views of parts to be hereinafter described. Figs. 8 and 9 are views in vertical section and in sectional front elevation of another embodiment of the invention. Fig. 10 is a detail view of the gearing for the 45 feed mechanism of Figs. 8 and 9.

In the drawings I have represented two forms of construction which embody the ge-

neric features of the present invention, and in the construction shown by Figs. 1, 2, 3, and 4 the set of feed-rolls is given a traversing 5 movement relative to the picker-cylinder in a path concentric with the axis of rotation of said cylinder, whereas the form of construction disclosed by Figs. 8 and 9 contemplates the employment of mechanism by which the set 5 of feed-rolls is given a traversing movement relative to the picker-cylinder in a path tangential to the periphery of said cylinder.

I will first proceed to describe the construction disclosed by Figs. 1 to 7, inclusive, 6 wherein the numeral 5 indicates a portion of the framework of a wool burring and picking machine, said framework being equipped with bearings 6, adapted to support the shaft 7 of a rotary picker-cylinder 8, the latter 6 having a multiplicity of teeth 9. The shaft of this rotary cylinder is adapted to be rotarilly driven in any suitable way, and said cylinder 8 may be of any preferred construction known to the art. In the embodiment 7 of the cylinder shown by the drawings it is built up of a series of disks having saw-teeth; but it will be understood that the active surface of said picker-cylinder may be formed by one or more toothed wires, as is well 7 known to the art. In front of the picker-cylinder is disposed a group or set of feed-rolls 10 11 12, which are disposed in operative relation to the periphery of the picker-cylinder, each roll being provided with a multiplicity of fine teeth. The rolls comprising 8 the set or group are of different diameters, and in the organization shown the roll 10 is larger than either of the rolls 11 12, while the roll 11 is of greater diameter than the roll 12. 8

In the form of construction disclosed by Figs. 1 to 7 the group of feed-rolls are mounted on swinging frames 13, one of said frames being shown more particularly by Fig. 5. This frame has an arm 14, provided with a 9 companion arm 15, whereby the frame may be fitted loosely on the shaft 7 of the picker-cylinder. Two of these frames 13 are employed, and they are loosely fitted on the

shaft 7 at opposite ends of the picker-cylinder, as shown by Figs. 2 and 3, said frames being thus capable of a swinging movement on the axis afforded by the picker-cylinder shaft. The frames 13 are provided with adjustable bearings 16, which accommodate the shaft 17 of the large feed-roll 10. The frames are furthermore provided with the upstanding posts 18, having bearings 19, which receive the shaft 20 of the feed-roll 11, and said frames are also provided with a post 21, having bearings 22 to accommodate the shaft 23 of the feed-roll 12. The bearings 16, with the posts 18 21, are adjustably connected to the frames 13, and this adjustable connection of the shaft-bearings to the frames may be effected by any suitable construction, one form of which is disclosed by Fig. 7, wherein the bearing is shiftable in a slot 13^a of the frame. The described method of attaching the shaft-bearings adjustably to the frame enables the feed-rolls 10, 11, and 12 of the group to be adjusted relatively to each other in an independent manner. The posts 18 serve to support the intermediate feed-roll 11 in a plane above and in co-operative relation to the large feed-roll 10, while the other posts 21 support the smaller feed-roll 12 of the group in a plane at one side of the rolls 10 11 and in quite close relation to the active surface of the picker-cylinder 8.

24 designates a doffing-brush, having a toothed active surface disposed in co-operative relation to the toothed surface of the large feed-roll 10, and this doffing-brush has a shaft 25, which is journaled in suitable bearings 26, adjustably secured to the swinging frames 13.

Any suitable means may be provided for positively rotating the set of feed-rolls; but I prefer to drive the rolls from the shaft 7 of the picker-cylinder, the latter being provided with a sprocket-wheel 27, with which engages a sprocket-chain 28, that serves to propel a sprocket-wheel 29, secured to an end portion of the shaft 20 of the intermediate feed-roll 11. This shaft 20 is provided at its opposite end with a sprocket-wheel 30, driving a sprocket-chain 31, which propels a sprocket-wheel 32, secured to a corresponding end of the shaft 23 of the small feed-roll. Said shaft 23 of the small feed-roll is provided with a spur-gear 33, which has intermeshing engagement with a large spur-gear 34, secured fast to an end portion of the shaft 17 of the large feed-roll 10. Thus the shaft 20 is driven directly from the picker-cylinder shaft, and it serves to propel the shaft of the small feed-roll, which in turn drives the shaft of the large feed-roll. The intermediate and small feed-rolls 11 12 rotate in the same direction; but the large feed-roll 10 rotates in an opposite direction to the feed-rolls 11 12 and to the

picker-cylinder 8. The doffing-brush 24 is positively driven by gear connections with the shaft of the large feed-roll 10, and this is secured by the employment of a sprocket-wheel 35, secured to the shaft 17 of the roll 10, which wheel impels a sprocket-chain 36, that engages with a sprocket-wheel 37 on the shaft 25 of the doffing-brush. 70

Any suitable mechanism may be employed to give the traversing movement to the swinging frames 13 and the set of feed-rolls mounted thereon, and in the drawings I have shown an appropriate driving mechanism whereby 75 this traversing movement may be given to the feed mechanism.

The frame 5 of the machine is equipped with bridges 38, on which are erected the vertical guides 39. These guides accommodate 80 slidable cross-heads 40, in which are journaled the end portions of a shiftable shaft 41. The bridges 38 are also provided with shaft-bearings 42, which accommodate the actuating-shaft 43, the latter being disposed below and 85 parallel to the shiftable shaft 41. The shaft 43 is equipped with elliptical gears 44, having intermeshing engagement with the spur-gears 45, secured on the shiftable shaft 41. The shaft 43 may be driven by a pulley and belt, 90 as shown by Fig. 2, and this shaft is thus adapted to rotate the elliptical gears 44, which impart the traversing movement to the shaft 41. On this shaft 41 are loosely fitted the lower ends of links 46, which have pivotal connection with adjustable blocks 47^a, that are secured to the swinging frames 13, and the sliding or up-and-down movement of the shaft 41 is communicated by the links 46 to the swinging frames 13, whereby the set of feed-rolls is given a traversing movement relatively to the surface of the picker-cylinder. 95 By pivotally mounting the swinging frames 13 for movement in an arc concentric with the axis of the shaft 7 the frames are adapted 100 to swing in an arc concentric with said shaft, and the construction and arrangement herein described secures a traversing movement of the set of feed-rolls in an arcuate path relative to the periphery of the picker-cylinder. 105 110

Any suitable or preferred means may be adopted to feed the wool into the set of feed-rolls; but I prefer to employ the endless carrier 47. (Shown by Figs. 1, 2, and 3 of the drawings.) This endless carrier is represented 115 of the slatted variety, and it is supported by a pair of drums or rollers 48 49. The roller 48 is secured firmly to a shaft 50, which is journaled in bearings 51 on the upstanding arms 52, attached to the swinging frames 13, (see Fig. 1,) and this shaft of the roller 48 is provided at one end with a spur-gear 53, the latter having intermeshing engagement with a spur-gear 54, secured firmly to the shaft 20 120

of the intermediate feed-roll 11, whereby this shaft 50 is driven directly from the feed-roll shaft 20 in a way to impart traveling movement to the slatted carrier 47. The other 5 drum or roller 49 of the carrier is an idle roller, and it is secured to a shaft 55, which is mounted in slidable bearings 56, the latter being loosely fitted in the slots 57 of the stationary posts 58 of the machine-frame. The 10 shafts 50 and 55 of the driving and idler drums 48 49 are maintained in fixed and parallel relation by the extensible arms 59, each arm consisting of two sections which are coupled by the threaded sleeves 60. Said sleeves 15 make provision for the endwise adjustment of the members forming the arms, and each arm has one end fitted loosely on the shaft 50 of the driving-drum 48, while the other end of the arm is fitted loosely on the shaft 55 of the 20 idler-drum 49. The adjustable bearings 56 and the extensible arms 59 make provision for the stretching of the endless slatted carrier to take up any slack therein.

It will be noted that the inner delivery end 25 of the slatted carrier is supported by a drum-shaft that is mounted on the swinging frames 13, while the idle drum-shaft is supported by movable bearings. This construction and arrangement allows the slatted carrier to swing 30 with the traversing movement imparted to the frames 13 and the set of feed-rolls, said carrier changing its position on the axis afforded by the shaft 55 of the idle carrier-drum, and the bearings of said shaft 55 being 35 slidable to accommodate the swinging movement of the carrier to the up-and-down traversing movement of the feed-roll frame. The endless carrier thus preserves its operative relation to the set of feed-rolls, and the 40 wool deposited on or supplied to the carrier is adapted to be delivered thereby at all times to said set of feed-rolls.

For most purposes it is advisable to drive the feed-rolls of the set or group in such a 45 manner that their peripheral speed is less than that of the picker-cylinder; but of course the feed-rolls must be driven at such peripheral speed that they will operate to secure continuous feeding of the wool to the picker-cylinder. The wool is carried in the well-known 50 manner from the belt to the feed-rolls, and these rolls in turn supply the wool to the picker-cylinder 8, the latter rotating at a speed somewhat faster than the feed-rolls and operating to catch the wool by means of the teeth 55 on the surface of said cylinder. The feed-roll 10 is considerably larger in diameter than the other two feed-rolls, so as to afford the largest possible surface and to hold the material 60 back as long as possible between the teeth of the feed-rolls, so that the fibers or filaments will be laid comparatively straight before

passing to the picker-cylinder. Assuming that the swinging feed-roll frame is at the lower limit of its travel and that the feed-rolls 65 and the picker-cylinder are in service, the shaft 43 is driven to make the elliptical gears impart the traversing movement in an upward direction to the feed-rolls and the frame relative to the picker-cylinder. Some of the wool 70 contained on the toothed surfaces of the roll 10 will be caught by the working surface of the picker-cylinder, and as this roll 10 is moved upwardly and as it also rotates in an opposite direction to the picker-cylinder the fiber will 75 be drawn out, because the wool for a certain length of time is subjected to the action of the quickly-turning saw-like teeth on the picker-cylinder and also to the pulling action of the set of feed-rolls having the traversing 80 movement relative to the cylinder, whereby the fibers without being caught or torn are stretched and are arranged straight and parallel, and in this manner the wool is thoroughly cleaned from burs, dirt, and other impurities, which preparation of the wool greatly 85 facilitates the subsequent carding thereof. When the wool lies on the picker-cylinder in the form of loose fleece, any dirt still remaining in it can be easily removed by the blast 90 of air from a fan 61. The shaft of this fan is journaled in appropriate bearings adapted to be driven by any suitable devices, and said fan is inclosed within a suitable casing 62, as 95 shown by Fig. 1. The wool may be taken off the picker-cylinder in any way and by suitable forms of devices known to those skilled in the art to which this invention relates; but as the present improvements have no connection with the wool-removing devices I have 100 not considered it necessary for the purposes of this specification to show and describe any kind of clearing devices for the picker-cylinder.

In the construction shown by Figs. 8 and 10 9 the parts are arranged in a somewhat different way for the purpose of imparting the traversing movement to the set of feed-rolls in a straight path substantially at a tangent to the periphery of the picker-cylinder. On 11 the bridge 38^a of the machine-frame are erected vertical stationary guides 63, adapted to receive the cross-heads 40^a, the same being provided with bearings for the reception of the shiftable shaft 41^a. Said shaft is provided 115 with gears 45^a, having intermeshing engagement with elliptical gears 44^a on the shaft 43^a, journaled in suitable bearings of the framework. This shaft 43^a is driven in any suitable way to rotate the gears, which operate 120 to impart the shiftable up-and-down movement to the shaft 41^a and to also rotate said shaft. Between the guides 63 are disposed the cross-heads 64, which receive the shaft 17^a

of the large feed-roll, and this shaft is operatively connected with the shiftable shaft 41^a by the frame 65, the latter having loose connection with the shafts 41^a and 17^a and adapted to support the large feed-roll, together with the parts that coöperate therewith. The cross-heads 64 are equipped with transverse bars 66, adapted to move or slide with the cross-heads. Loosely connected with the feed-roll shaft 17^a are the pairs of links 67 68, and these links are disposed in oppositely-inclined positions to extend across the bars 66, said links having pivotal connection at 69 with said bars 66. The links 67 extend above the large feed-roll and support or carry the shaft of the intermediate feed-roll 11^a, while the other links, 68, support the shaft of the small feed-roll 12^a. These feed-rolls are disposed or grouped in the order heretofore described with reference to the feed mechanism shown by Figs. 1 to 4, inclusive; but I prefer to employ other forms of gearing, whereby the set of feed-rolls may be driven from the rotary and shiftable shaft 41^a. This shaft is provided with a spur gear-pinion 70, with which meshes a large gear 71 on the shaft 17^a of the large feed-roll, and with this feed-roll shaft 17^a is associated a train of gears for driving the intermediate and smaller feed-rolls. On the shaft 17^a is secured a gear-wheel 72, which meshes with a gear-wheel 73 on the roll-shaft 20^a, and a gear-wheel 74 on the roll-shaft 23^a meshes with said gear 72, (see Fig. 10,) said gearing being arranged to drive the rolls 11^a and 12^a in the same direction, while the large roll 10^a rotates in an opposite direction to said rolls 11^a and 12^a. The employment of the adjustable links 67 68 allows the feed-rolls to be adjusted to different positions relatively to each other. The operation of the mechanism shown by Figs. 8 and 9 is similar to that of the mechanism shown by Figs. 1 to 4, inclusive, and need not be further described.

I find by practical use of the machine that the traversing movement of the set of feed-rolls relative to the picker-cylinder is a decided advantage, because I am able to materially reduce the waste of the wool which is caused by some of the prior machines of which I have knowledge. The fibers of the wool are drawn out or combed, so as to produce the desired long staple. The fibers are not broken, and the machine is especially useful on short wool which is full of burs and dirt. The large feed-roll 10 of my machine rotates at a speed less than that of the picker-cylinder and in an opposite direction thereto, and this roll, along with the remaining feed-rolls of the set, is moved in a path adjacent to the surface of the picker-cylinder, so that the wool will be drawn out and combed by

the teeth on the surfaces of the cylinder and the feed-roll 10, the wool being caught on and retained by the teeth of said roll 10 for a period sufficient to secure the desired drawing and combing thereof.

Having thus described my invention, I claim as new and desire to secure by Letters Patent—

1. A wool picking and burring machine having a picker-cylinder, a set of feed-rolls adjacent to said picker-cylinder, and means for imparting a traversing movement to said set of feed-rolls relatively to the active surface of said cylinder.

2. A wool picking and burring machine having a picker-cylinder, a set of feed-rolls of different sizes, and means for bodily imparting a traversing movement to the entire set of feed-rolls relative to the picker-cylinder.

3. A wool picking and burring machine having a picker-cylinder, a set of feed-rolls, means for imparting a traversing movement to said feed-rolls in a path concentric with the active surface of the cylinder, and a suitable blower arranged to direct a blast of air against the material on the cylinder.

4. A wool picking and burring machine having a picker-cylinder, a swinging support movable on an axis coincident with that of the cylinder, a set of feed-rolls carried by said swinging support and movable therewith in a path concentric with the active surface of the cylinder, and mechanism for positively moving the support and the set of feed-rolls to impart a traversing movement thereto.

5. A wool picking and burring machine having a picker-cylinder, a feed-roll of large diameter adjacent thereto, another feed-roll co-operating with the first-named feed-roll, a small feed-roll disposed between the picker-cylinder and the other two feed-rolls, means for supporting all the feed-rolls of the set, and means for bodily shifting the support and the set of feed-rolls relative to the cylinder.

6. In a wool picking and burring machine, the combination with a picker-cylinder, of a swinging support, a set of feed-rolls mounted on the support, one of said feed-rolls being disposed between the picker-cylinder and the other feed-rolls of the set, a doffing-brush carried by the support, and means for imparting traversing movement to said support and the feed-rolls and doffing-brush thereon.

7. In a wool picking and burring machine, the combination with a picker-cylinder, of a set of feed-rolls, means for imparting a traversing movement to said feed-rolls relative to the picker-cylinder, and a feed device shiftable with said feed-rolls.

8. In a wool picking and burring machine, the combination with a picker-cylinder, of a set of feed-rolls, means for imparting a traversing movement to said feed-rolls relative to

the picker-cylinder, and an endless carrier having one end connected with a part of the feed-roll mechanism and shiftable with said feed-rolls in its traversing movement.

- 5 9. In a wool picking and burring machine, the combination with a picker-cylinder, of a movable feed-roll carrier, a set of feed-rolls mounted in said carrier, means for imparting movement to the carrier and the feed-rolls in
10 a way to secure a traversing movement of the feed-rolls relative to the picker-cylinder, an endless carrier, a conveyer-driving roller mounted on said shiftable carrier and geared to one of said feed-rolls, and an idler conveyer-

roller operatively fitted to the endless conveyer and serving as the axis of motion of the conveyer in its adjustment with the feed-roll carrier, one of said conveyer-rollers being adjustable to maintain the conveyer in a taut condition.

In testimony whereof I have signed my name to this specification in the presence of two subscribing witnesses.

GEORGES PROUVOT.
